George B. Hanford Inventor
By his Attorney, Rev. T. Rauber

UNITED STATES PATENT OFFICE.

GEORGE B. HANFORD, OF BLOOMFIELD, NEW JERSEY.

RECEPTACLE AND LINING THEREFOR.

Application filed September 27, 1922. Serial No. 590,799.

To all whom it may concern:

Be it known that I, GEORGE B. HANFORD, a citizen of the United States, residing at Bloomfield, in the county of Essex and State of New Jersey, have invented certain new and useful Improvements in Receptacles and Linings Therefor, of which the following is a specification.

This invention relates to receptacles for receiving liquid or moist materials such as garbage and refuse and, more particularly to a moisture proof lining for garbage cans and similar receptacles.

When refuse containers, such as garbage pails, are emptied there is a tendency for a portion of their contents to stick to the walls of the container, no complete cleaning of the pails being ordinarily attempted on the part of those removing such material. As the washing of the receptacles would be a disagreeable and usually undesirable operation, the material sticking to the inner wall of the container is permitted to remain creating a disagreeable, unsanitary condition and tending to rust the pail.

An object of the present invention is to protect the inner surface of receptacles of this class from direct contact with the materials contained therein.

Another object of the invention is to provide a substantially moisture proof or water proof lining for garbage pails and similar receptacles adapted to protect the inner surface of the container from direct contact with the materials stored therein and which may be readily inserted in the receptacle and may be removed with the contents of the receptacle when being emptied.

It is desirable to construct these liners of light, flexible material, such as waxed or water proofed paper, and, to protect this lining against rupture or tearing, it is usually necessary that the paper closely fit the inner surface of the container, in order that it may not be subjected to a tearing strain. As the sizes and dimensions of the receptacles vary considerably, a lining capable of being expanded or contracted to closely fit receptacles of different diameters is desirable when the linings are to be sold for general use.

Accordingly, a further object of the invention is to provide a flexible lining substan-

tially impervious to moisture and capable of being fitted to receptacles of different dimensions.

A still further object of the invention is to provide a lining with folded or plaited walls readily insertable into a receptacle and readily expandable to uniformly fit walls of different diameters.

With these and other objects in view, the invention comprises the device described and set forth in the following specification and claims.

The various features of the invention are illustrated in the accompanying drawings, in which;

Fig. 1 is a view, partly in vertical section, of a receptacle and lining embodying a preferred form of the invention,

Fig. 2 is a side view of the lining in folded position in which it may be packed or stored,

Fig. 3 is a side view of the lining partly expanded and ready to be inserted in a receptacle,

Fig. 4 is a top or plan view of the lining expanded to approximately the position shown in Fig. 3,

Fig. 5 is a side view of the lining expanded to the dimensions which it occupies when in position in the receptacle.

Fig. 6 is a view similar to that of Fig. 3 of the lower portion of a lining illustrating a modified way of closing the lower end of the lining,

Fig. 7 is a view on the line 7—7 of Fig. 6, and,

Fig. 8 is a top or plan view of a partly folded lining illustrating a different manner of forming the folds or pleats of the lining.

In the present invention the weight and lateral pressure of the material contained in the receptacle is sustained by the receptacle wall but direct contact with the surface of the receptacle is avoided by the interposition of a thin sheet of moisture proof paper or other suitable material between the contained material and the inner surface of the container. This protecting sheet or lining is preferably made in the form of a cylinder closed at one end and of a length somewhat greater than the height of the receptacle. The cylinder is folded or pleated in such a manner that it may be folded or packed in

2
 long, rod like, packages bound together at one end, that it may be slightly expanded from this folded position, inserted in a receptacle and then expanded uniformly throughout its circumference until it contacts throughout with the surface of the receptacle.

Referring more particularly to the accompanying drawings, the lining is formed of a sheet of paper 10 having a width somewhat greater than the circumference of the largest container to which it is to be fitted and a height considerably greater than the height of the container. Any paper or sheet material capable of resisting the absorption or penetration of moisture for the period of time it is to be used may be employed for this purpose. It is not necessary that the paper be strong enough to sustain the weight of the receptacle contents.

The vertical edges of the paper 10 are joined in a folded or otherwise water proof joint 12 which may be fastened by means of a suitable adhesive or preferably by means of binding clips or rivets 14 at suitable intervals. A series of vertical folds or pleats 16 is then formed in the cylinder. For cylinders of large diameter these pleats are formed in two sets lying side by side while for smaller sizes the two sets of pleats may be interfolded as shown in Fig. 8. The cylinder may then be tightly folded into a narrow elongated package as shown in Fig. 2, the lining being conveniently packed in this form for transportation and sale.

When in the closely packed form illustrated in Fig. 2, the lower end of the lining may be conveniently formed by joining the ends of the pleats in a tight, substantially water proof joint as at 18, and fastening them with a rivet 20 or other suitable binding means. With some sizes and pleat constructions it is preferable to turn or fold a short portion 22 upwardly and pass the rivet or binder through the folded and adjacent unfolded portions to thereby obtain a tighter joint. Instead of the rivet or binder illustrated in Figs. 2 and 3, the end of the tube or cylinder may be bound and fastened by winding a wire or other binding means 24 around the end of the pleats as shown in Figs. 6 and 7.

In placing the lining in a receptacle, the cylinder is opened slightly as indicated in Fig. 4, and the closing joint 18 is placed at approximately the center of the bottom 26 of a container 28, Fig. 1. The sides of the cylinder are then pressed radially outward until they reach a seam 30 between the bottom 26 and side wall 31 of the container and are then spread upwardly against the inner surface of the wall 31. If the diameter of the container is smaller than the diameter of the cylinder when fully expanded, the edges of the lining may extend inwardly

from the wall of the receptacle but the contacting portion of the lining is uniformly pressed against the surface of the receptacle and there is therefore no tearing strain on the lining.

The lining is preferably long enough to extend above the upper rim, 32 of the receptacle and is bent outwardly and downwardly to form an overlapping portion 34 which holds the lining in place and prevents it from falling inwardly and exposing the inner surface of the receptacle. The flexible character of the lining facilitates the formation of the overlapping portion without danger of tearing the fabric of the lining. When the receptacle is to be emptied, this edge is turned inwardly and the lining removed with the contents of the receptacle and replaced by a new lining. A deodorant and disinfectant material such as carbolic acid or other suitable material may be incorporated in the paper or lining fabric together with the water proofing material when desired.

It will be understood that this invention may be applied to other types of receptacles than those mentioned and may, in some cases, be used to render containers water proof.

Having described the invention, what I claim and desire to secure by Letters Patent is:

1. A device of the kind described which comprises a receptacle lining having pleated walls of flexible material substantially non-permeable to water, the pleats extending longitudinally when folded, adapted to closely fit the inner surfaces of the bottom and side walls of receptacles of different dimensions and when expanded converging at one end to a substantially moisture proof closure.

2. A device of the kind described which comprises, a receptacle lining having a bottom portion of substantially non-permeable material having pleats extending radially outward and side walls formed by an upward extension of said material and said pleats, said pleats extending longitudinally of the length of the lining when folded.

3. A device of the kind described which comprises, a receptacle lining of water proof paper formed into a cylinder with pleated walls, the pleats of said walls extending longitudinally when folded, and gathered at one end to a water proof closure to form a bottom portion.

4. A device of the kind described which comprises, a receptacle lining of water proof material containing a deodorant, formed into a cylinder with pleated walls and gathered at one end to a water proof closure to form a bottom portion, the pleats of said walls extending longitudinally when folded, and when expanded extending radially from

the central closure to form a bottom portion and longitudinally upwards to form side wall portions.

5. A receptacle of the kind described having a flexible walled pleated lining of moisture proof material, the pleats of said walls extending longitudinally when folded, the upper end of said wall being adapted to fold

over the rim of the receptacle when expanded and the lower portion of whose walls is 10 gathered to a substantially moisture proof joint resting on the bottom surface of said receptacle.

In testimony whereof I affix my signature.

GEORGE B. HANFORD.
